UNITED STATES PATENT OFFICE.

WILLIAM C. ANDERSON, OF TOLEDO, OHIO, ASSIGNOR TO THE AMERICAN CUT GLASS COMPANY, OF CHICAGO, ILLINOIS.

DESIGN FOR A GLASS DISH.

SPECIFICATION forming part of Design No. 27,060, dated May 18, 1897.

Application filed March 20, 1897. Serial No. 628,544. Term of patent 7 years.

To all whom it may concern:

Be it known that I, WILLIAM C. ANDERSON, of Toledo, county of Lucas, and State of Ohio, have invented a certain new and original Design for a Glass Dish; and I do hereby declare that the following is a full, clear, and exact description of the invention, which will enable others skilled in the art to which it appertains to make and use the same, reference being had to the accompanying drawings, and to the figures of reference marked thereon, which form part of this specification.

This design relates to a glass dish, and particularly to the ornamentation of the exterior surface thereof.

The drawings represent, in Figure 1, a bottom plan view of a dish containing the design, and in Fig. 2 a section on line xx , Fig. 1.

The design is applicable to dishes, plates, and bowls.

The leading features of my design are a central hexagonal stud inscribed within a hexagon, described by radial curved lines terminating at the edge of the dish, each line radiating in inverse order from the center of the dish in the arc of a circle, whereby the inverse curvatures form obovate fields with curved lines in segments of a circle radiating from an intersection with the radial curved lines in parallelism to the arc of the circle to form obovate fields of less area alternating with the fields of greater area with prismatic studs centrally thereof, and triangular lines, the fields of the obovates of greater area of conoidal form being embellished with a hexagonal border of prisms and intersecting lines, with a border of radial fan lines and intermediate checkering, the central hexagon being surrounded by six prismatic studs which fill the space at the intersection of the segmental central lines with the radially-curved lines.

1 designates a central hexagonal stud in-

scribed within a hexagon 2, formed by radial lines 3, terminating at the edge of the dish. Each line 3 radiates from the hexagon in the arc of a circle, whereby the consequent inverse curvature forms obovate fields 4. Intersecting the radial lines 3 are lines 5, which describe the segment of a circle in parallel relation with the radial lines in describing the arc of a circle of greater area and form obovate fields 6 of less area than fields 4 and alternating therewith. Fields 6 are formed with prismatic studs 7, centrally of the field and triangular lines 8 to form prisms. The fields 9 of the obovates of greater area are of conoidal form and extend to the smallest diameter described by the scallop of the edge of the dish and are embellished with a hexagon 10, in which are prisms 11 and intersecting lines. The border of the dish comprises six scallops 12, each of which is embellished with radial fan lines 13 with intermediate checkerings, forming prisms. Intermediate the hexagons 10 are hexagonal fields 14 with prismatic studs and projecting lines to form a plurality of triangular prisms.

The hexagonal fields and prismatic studs with the alternating hexagonal fields with the six prismatic studs and the obovate fields of different area described by lines in the arc of a circle lend a pleasing effect to the design.

What I claim is—

The design for a glass dish, substantially as shown and described.

In testimony that I claim the foregoing as my own I hereby affix my signature in presence of two witnesses.

WILLIAM C. ANDERSON.
